SHUTTLE BOX FOR LOOMS

Willie H. Binette, Manchester, N. H., assignor of thirty-seven and one-half per cent to Albert Lessard, and twenty-five per cent to Emile Lemelin, both of Manchester, N. H.

Application February 21, 1933, Serial No. 657,858

3 Claims. (Cl. 139—185)

The present invention relates to new and useful improvements in shuttle boxes for looms of the filling replenishing type and has for its primary object to provide, in a manner as hereininafter set forth, a shuttle box embodying a novel construction and arrangement through the medium of which the old or spent filling will be prevented from being caught between the shuttle and the front wall of the box upon call for replenishment and subsequently carried into the shed.

Other objects of the invention are to provide a front plate for shuttle boxes of the aforementioned character which will be simple in construction, strong, durable, highly efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in top plan of a shuttle box including a front plate in accordance with the present invention.

Figure 2 is a view in side elevation of the front plate.

Figure 3 is a view in vertical transverse section, taken substantially on the line 3—3 of Figure 2.

Figure 4 is a view in elevation, looking at the inner side of the front plate constituting the present invention.

Figure 5 is an elevational view of the front plate, showing the same removed from the lay.

Figure 6 is a view in top plan of the front plate.

Figure 7 is a view in longitudinal horizontal section, taken substantially on the line 7—7 of Figure 4.

Figure 8 is a view in vertical transverse section, taken substantially on the line 8—8 of Figure 6.

Referring now to the drawings in detail, it will be seen that the reference numeral 1 designates generally the shuttle box and 2 indicates a conventional shuttle having a longitudinal groove 3 in its forward or front side which accommodates the filling. The shuttle box 1 includes the usual pivoted binder 4 engageable with the shuttle 2.

The front plate 5, which constitutes the present invention, comprises slotted ears 6 on its end portions which accommodate bolts 7 for adjustably securing said front plate in position on the lay. On the inner side of the front plate 5 is a lining 8 of suitable material, preferably leather, for contact with the shuttle 2.

The inner side of the front plate 5 has formed therein longitudinally aligned channels 9 which permit channels 10 to be embossed or pressed into the lining 8, said channels 10 being opposed to the channel 3 when the shuttle 2 is in the box 1 for accommodating the filling.

At an intermediate point, the front plate 5 is provided, in its inner side, with a cut out 11 with which the channels 9 and 10 communicate and which extends to the lower edge of said front plate 5. The lining 8 is also provided with a cut out 12 which is substantially similar to the cut out 11 and which is in registry with said cut out 11.

At the ends of the cut out 11, the front plate 5 has formed therein openings 13 for the passage of tabs 14 which are integral with the lining 8. The tabs 14 are secured, as at 15, on the outer, or front, side of the plate 5 for retaining the intermediate portions of the lining 8 tightly against said plate 5.

With shuttle boxes in widespread use at present, it has been found that, during replenishment, the old or spent filling gets out of the opposed channels provided therefor in the shuttle and the front plate of the box and binds between said shuttle and front plate to be subsequently carried into the shed, resulting in defective cloth. With a front plate constructed in accordance with this invention, it has been found that this difficulty is overcome as the cut outs 11 and 12 in the plate 5 and the lining 8, respectively, accommodate the old or spent filling and prevent it from being caught between the shuttle and the front plate of the shuttle box.

It is believed that the many advantages of a front plate for shuttle boxes constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A shuttle box plate having an elongated cut out therein and further having openings thereto substantially at the ends of the cut-out, a lining mounted on the inner side of the plate having an elongated cut-out therein communicating with the first-named cut-out, said cut-outs, for the reception of filling, the lining further having longitudinally aligned channels therein for the reception of the filling, said

channels communicating with the second-named cut-out, and tabs integral with the lining extending through the openings and secured to the outer side of the plate.

- 5 2. A shuttle box plate having longitudinally spaced openings therein, a lining mounted on the inner side of the plate and secured, at its ends, to the end portions of said plate, said lining having a longitudinally elongated cut-out 80 therein, and tabs, integral with the end walls of the cut-out, extending through the openings and anchored to the outer side of the plate.
- 10

3. A shuttle box plate having longitudinally spaced openings therein, a lining mounted on the inner side of the plate and secured, at its ends, to the end portions of said plate, said lining having a longitudinally elongated cut-out 80 therein, integral tabs on the end walls of the cut-out extending thru the openings, and means on the outer side of the plate intermediate the openings for anchoring the free ends of the tabs to the plate.
